ington, N. J., a corporation of New Jersey

Application August 27, 1943, Serial No. 500,218

17 Claims. (Cl. 12—14)

This invention relates to machines for use in the manufacture of shoes for shaping uppers over lasts or other forms. An object of the invention is to provide a machine for shaping the heel ends of uppers in such manner that preformed heels later applied in contact with the uppers on the heel seats will fit the uppers in accordance with the requirements of the best shoemaking. With this and other objects in view, the invention is herein illustrated as embodied in a novel heel-end lasting machine in the use of which the lasting operation is performed by the operator; but it will be understood that novel features of the invention are likewise applicable to power-operated machines and that in other respects also the invention is susceptible of various embodiments.

A preformed heel, such as a wood heel, applied in contact with an upper on the heel seat of a shoe should, for the best results, fit the upper in such manner that the contour of the heel is practically a continuation of the contour of the upper heightwise of the shoe without any substantial break at the junction of the heel and the upper. To this end, it is desirable that the upper shall be so formed as to present a definite edge line about the heel seat, and that the contour of the edge line of the heel seat shall correspond substantially to the edge contour of that portion of the heel which engages the upper at the heel seat. For the accomplishment of these results the present invention, in one aspect, provides a flexibly adjustable mold arranged to extend about the heel end of an upper on a form and by contact with the upper adjacent to the edge of the heel seat to establish a definite edge line on the upper about the heel seat upon the application of compacting pressure heightwise of the form to an inturned marginal portion of the upper, and a templet for determining independently of the form the contour lengthwise of the edge of the heel seat of that portion of the mold which engages the upper adjacent to the edge of the heel seat. The templet has a contour geometrically similar to the desired contour of the edge line of the heel seat and engages a portion of the mold to adjust the mold as the latter is applied about the heel end of the upper. In the construction herein shown the templet conveniently serves also as a member for applying pressure to the inturned margin of the upper as above described, but it will be understood that both functions need not be performed by the same member. Combined with the parts above described, in the illustrative embodiment of the

invention, are wipers which are operated to wipe the margin of the heel end of the upper inwardly over an insole and which are retracted from over the heel seat before the mold is applied about the heel end of the upper, cement being preferably used to retain the margin of the upper in overwiped position. In the construction shown the wipers comprise a plurality of members which are moved inward rectilinearly in converging paths and serve to localize between them any pleats that develop in the margin of the upper, and they are so formed as to trim off the tops of these pleats and thus to provide a better surface to receive the heel. It should be understood that in the provision of such wiping and trimming means the invention is not necessarily limited to mechanism which operates on the heel ends of uppers.

The above and other features of the invention, including various novel details of construction and combinations of parts, will now be more particularly described with reference to the accompanying drawings and thereafter pointed out in the claims.

25 In the drawings,

Fig. 7 is a section on the line VII—VII of Fig. 4;

Fig. 8 is a view similar to Fig. 4 of a portion of the structure, but showing the parts as they appear when the wipers are at the limits of their inward wiping movements over a shoe in the machine;

Fig. 9 is a section on the line IX—IX of Fig. 8, showing also the templet;

40 Fig. 10 is a view similar to Fig. 9, but showing the parts as they appear later in the operation of the machine;

Fig. 11 is a view similar to Fig. 10, but illustrating conditions still later in the operation;

45 Fig. 12 is a vertical sectional view illustrating the trimming of the pleats formed in the margin of the upper; and

Fig. 13 is a perspective view of the heel-end portion of a shoe after it has been operated upon by the machine.

The machine in which the invention is herein illustrated as embodied is provided with a lower frame 2 having fast thereon an intermediate casting 4 to which is secured a head casting 6. Secured to the head casting by screws 8 is a hold-down 10 the lower end of which is arranged to engage the heel end of the insole of a shoe on a last to determine the height at which the shoe is positioned for the operation of the machine thereon. Slots 12 in the hold-down, through which the screws extend, permit it to be adjusted vertically. Mounted for vertical movement beneath the hold-down in the casting 4 is a shoe-supporting rod 14 on the upper end of which is detachably mounted a block 16 having a pin 18 arranged to extend into the spindle hole in the heel end of the last. A flange 20 on the rod 14 engages the casting 4 to limit downward movement of the rod. The rod 14 is moved upwardly to clamp the shoe against the hold-down 10 by means of a treadle 22 pivoted at 24 on the frame 2 and provided with a roll 26 arranged to engage the lower end of a rod 28 movable in a bearing 30 on the frame. The rod 28 engages and lifts the rod 14 in response to depression of the treadle. To hold the shoe in clamped position when the treadle is released, there is provided a locking member 32 fast on a shaft 34 rotatable in bearings in the front of the casting 4, the shaft having also fast thereon a hand lever 36. An eccentric face 38 on the member 32 is arranged to engage an inclined front face 40 on the rod 14 to lock the rod frictionally against downward movement in response to upward movement of the hand lever 36.

After the shoe has been clamped and secured against the hold-down 10 its heel end is lasted by means which will now be described. Before the shoe comes to the machine it will already have been lasted at the shank portion, at least in the vicinity of the heel breast line; and preferably, although not necessarily, the heel end of the upper materials will include a counter previously molded to provide an inturned heel-seat flange. Preferably also cement applied to the different layers of the heel-end portion of the upper materials will be used to secure the heel end of the upper in lasted position. For wiping the margin of at least the outer layer of the upper inwardly over the insole the machine is provided with a plurality of wipers comprising a pair of side wipers 42, a pair of corner wipers 44 and an end wiper 46. The two side wipers 42 are secured to the lower faces of wiper carriers 48 which are slidably movable rectilinearly in guideways formed in a plate 50 supported partly by shelves 52 on the head casting 6 and partly by vertical rods 54 secured to the casting 4. Similarly, the corner wipers 44 are secured to wiper carriers 56 and the end wiper 46 to a wiper carrier 58, these wiper carriers likewise being rectilinearly movable in guideways in the plate 50. The inner end portions of the wiper carriers have inclined upper faces, as shown in Fig. 3 with reference to the carriers 48, and accordingly in Figs. 6 and 7 the carriers there shown appear partly in section and partly in elevation. The several guideways for the wiper carriers are so arranged that in operating on the upper the wipers move inwardly in converging paths until they meet over the margin of the upper on the heel seat. For operating the side wipers 42 and the corner wipers 44 there are provided levers 60 pivotally mounted between their front and rear ends on vertical studs 62 secured to the plate 50. The

levers 60 are connected to the wiper carriers 48 by links 63 and pins 64, the pins extending through slots in the plate 50, and they are similarly connected to the wiper carriers 56 by links 66 and pins 68. The end wiper 46 is operated by a third lever 70 one arm of which is connected to the end wiper carrier 58 by a link 72 and a pin 74, this lever being pivotally mounted on a vertical stud 76 extending upwardly from the plate 50. The other arm of the lever 70 is connected by a link 78 to the rear end of the left-hand lever 60. The rear arms of the two levers 60 are bifurcated and carry rolls 80 engaged by a cam 82 which is mounted to turn on a stud 84 on the plate 50. A spring 86 connected to the rear arms of the levers tends to swing these arms toward each other and thereby holds the rolls 80 at all times against the cam 82. This cam is so formed that when it is turned in a clockwise direction (Fig. 4) it operates the levers 60 to impart inward wiping movements to the several wipers, the end wiper 46 being operated from the left-hand lever 60 through the link 78 and the lever 70. The cam is turned by a hand lever 88 mounted on the stud 84 and connected to the cam by a pin 90.

By reference to Figs. 4 and 8 it will be observed that the opposite side edges of each of the two corner wipers 44 and of the end wiper 46 extend inwardly in such convergent relation that the edges of the wipers 44 and 46 which meet over the heel seat, and also the meeting edges of the wipers 44 and 42, are parallel to each other. It will be evident that as the several wipers are moved inwardly in converging paths, any pleats that are formed in the margin of the upper, especially in the outer layer of the upper materials if the counter has a molded in-turned flange, will be localized between the wipers 42 and 44 and between the wipers 44 and 46. In order to provide a better surface to receive the heel, the wipers are so formed as to trim off the tops of these pleats by a shearing action thereon substantially at the end of the wiping operation. For this purpose the opposite side edges of each of the wipers 44 are formed as cutting edges 92 (Fig. 7) which co-operate with shearing edges 94 and 96 on the side wipers 42 and the end wiper 46 respectively (see Fig. 12).

After the wipers have been operated as above described, they are retracted from over the shoe by the spring 86 in response to reverse movement of the hand lever 88, and a mold 98 is applied about the heel end of the upper in a relation to the shoe determined by a templet 100 which serves also as a pressing member for pressing the overwiped margin of the upper down on the insole. The mold 98 comprises a substantially U-shaped metal band 102 which is flexible and resilient, a pad 104 of comparatively soft rubber secured to the band, and a mold member 106 also secured to the band and made of hard rubber or other suitable material sufficiently flexible to permit it to assume different contours lengthwise of the edge of the heel seat, yet hard enough definitely to shape or mold the upper by pressure against it. The mold member 106 when applied to the shoe is arranged to engage the upper opposite the edge face of the insole and adjacent to the edge of the heel seat, and the pad 104 is arranged to extend farther heightwise of the shoe in clamping engagement with the upper. Both the position of the mold lengthwise of the shoe and the contour of the mold member 106 lengthwise of the edge of the heel seat are determined

by the templet 100 which has a peripheral face 108 (Fig. 9) arranged to be engaged by a marginal portion of the band 102 extending upwardly beyond the member 106, the face 108 having a contour geometrically similar to the desired contour of the edge line of the heel seat. It will be understood that the pad 104 is sufficiently yieldable not to prevent the mold from being positioned and adjusted as determined by the templet.

For supporting the mold 98 and for moving it toward and from the shoe there is provided a slide 110 guided, as hereinafter described, for movements in directions lengthwise of the shoe. Supported by ears 112 (Fig. 5) on the front end of the slide 110 is a horizontal rod 114 on the opposite ends of which are mounted forwardly extending arms 116 secured together by a top plate 118 for swinging movements as a unit about the rod 114 for a purpose hereinafter explained. At their front ends the arms 116 carry upwardly extending studs 120 to which the plate 118 is also secured, these studs serving as pivotal supports for other forwardly extending arms 122 to which outwardly and rearwardly curved end portions of the band 102 are secured. Screws 124 threaded in rearwardly extending tail portions 126 of the arms 122 are arranged to engage webs 128 on the arms 116 to limit outward swinging movements of the arms 122. The band 102 is of such normal shape that the shoe-receiving opening at the front end portion of the mold is wider than the heel end of a shoe, and when the mold is applied to the shoe by a forward movement of the slide 110 the pressure of the heel-end face of the shoe against the pad 104 causes the arms 122 to swing inwardly toward each other to bring the portions of the mold at the sides of the heel end of the shoe to the positions determined by engagement of the templet 100 with the upper marginal portion of the band 102.

The mold-supporting slide 110 is moved horizontally by means hereinafter described along guideways on a supporting block 130. To position the mold clear of the wipers when they are operated, it is initially inclined in a downward and forward direction, as illustrated in Figs. 1 and 9, and as it is moved forwardly toward the shoe by the slide 110 after the wipers have been retracted it is swung upwardly to a horizontal position. For this purpose the left-hand mold-supporting arm 116 has integral therewith a rearwardly extending arm 132 provided with a roll 134 extending inwardly under a projection 136 on the block 130 and arranged to be engaged by a cam face 138 on this projection to impart upward swinging movement to the mold about the rod 114 in response to the forward movement of the slide 110. A horizontal face 140 on the projection 136 serves thereafter by engagement with the roll to determine the proper horizontal position of the mold. To insure proper clearance between the upper edge of the band 102 and the end wiper 46 a slot 142 is provided in the band.

The lower face of the block 130 is inclined in a downward and rearward direction and the block is mounted on correspondingly inclined guideways 144 on another block 146 guided for horizontal movements lengthwise of the shoe on the casting 4. A pin 148 fast in the casting 4 extends upwardly through an opening 150 in the block 146 into a hole 152 in the block 130 and accordingly holds the block 130 against movement in directions lengthwise of the shoe while permitting it to move upwardly or downwardly. By such upward or downward movement of the block 130,

which is effected by movement of the block 146 lengthwise of the shoe, the mold 98 is adjusted to position it at the proper height relatively to the shoe. The adjusting movement of the block 146 is effected by a screw 154 which is threaded in the block and turns in a bearing 156 on the casting 4. A flange 158 formed on the screw at one side of this bearing and a nut 160 threaded thereon at the other side of the bearing prevent any longitudinal movement of the screw. The screw may be turned by means of the flange 158, after which the nut 160 may be tightened to hold the block 146 in adjusted position.

The slide 110 is moved forwardly to carry the mold 98 toward the shoe and to apply it to the shoe by means of a manually operated arm 162 fast on a rockshaft 164 mounted in bearings in the casting 4. Another arm 166 fast on this rockshaft is connected by a link 168 to the slide 110. To hold the mold securely in operative position there is provided a pawl 170 carried by a third arm 172 on the rockshaft and arranged to engage the teeth of a ratchet member 174 on the casting 4, the pawl being held against the teeth by a spring 176.

The combined templet and upper-pressing member 100 is supported on the lower end of a bar 178 vertically movable in bearings in the head casting 6. For moving this bar and the member 100 downwardly and upwardly there is provided a pinion 180 in engagement with rack teeth on the bar, the pinion being fast on a shaft 182 mounted in a bearing in the casting 6. A rod 184 mounted in a head 186 on the shaft serves as a crank for turning the pinion. The member 100 is so mounted as to permit it to turn, for a purpose hereinafter described, about a reduced lower end 188 of the bar 178 the axis of which is in line with the axis of the last pin 18. It is held detachably in position on the bar by a spring-pressed pin 190 the inner end of which extends into an annular groove 192 in the reduced end of the bar. Different members 100 may therefore be readily substituted for shoes of different sizes or styles.

In the operation of the machine, the operator mounts the shoe and last on the last pin 18 and by depression of the treadle 22 moves the rod 14 upwardly to clamp the shoe against the hold-down 10, after which he raises the hand lever 36 to lock the rod 14 against downward movement by frictional engagement of the locking member 32 with the rod. By means of the hand lever 38 he then moves the several wipers 42, 44 and 46 inwardly in converging paths to wipe the margin of the heel end of the upper over the insole, as illustrated in Figs. 8 and 9. As the wipers are thus moved inwardly any pleats which are formed in the margin of the upper, especially in the outer layer of the upper materials, are localized between adjacent wipers, and near the end of the wiping operation the tops of such pleats are trimmed off by the cutting edges 92 and the co-operating shearing edges 94 and 96 of the wipers, as illustrated in Fig. 12. Thereafter the operator swings the hand lever 38 reversely to cause the wipers to be retracted from over the heel seat, the cement previously applied to the upper being depended upon to retain its margin substantially in overwiped position. By means of the crank 184 he then lowers the combined templet and pressing member 100 to a position almost, if not quite, in contact with the overwiped margin of the upper, and by swinging movement of the arm 162 applies the mold 98 about the heel

end of the shoe, the mold being moved forwardly by the slide 110 and swung upwardly by the action of the cam face 133 on the arm 132. As the mold is thus applied to the shoe its position lengthwise of the shoe and the contour lengthwise of the edge of the heel seat of its upper-molding portion 106 which engages the upper adjacent to the edge of the heel seat are determined by engagement of the peripheral face 108 of the templet 100 with the upper marginal portion of the band 102 (Fig. 10), the soft rubber pad 104 of the mold yielding sufficiently to permit this. By reason of the manner in which the mold is supported it has enough freedom for lateral angular movement to permit it to adjust itself upon contact with each shoe in accordance with any such small variations as there may be in the positions of different shoes about the axis of the last pin 18, and the provision for turning movement of the templet 100 about that axis permits the templet correspondingly to assume the proper relation to each shoe as it is engaged by the band 102 of the mold.

After the mold 98 has been applied to the shoe as above described, it is held in operative position by the pawl 170. While it is in that position the operator turns the pinion 180 to force the member 100 farther downwardly and thus to apply heavy pressure to the overlaid margin of the upper. This pressure serves to compact the layers of upper materials over the insole and to provide an even surface to receive the heel. It also tends to squeeze the upper outwardly against the mold member 106, and this member accordingly serves to establish a definite edge line on the upper about the heel seat, the contour of this edge line being determined by the templet member 100 in accordance with the edge contour of the upper-engaging portion of the heel to be thereafter applied to the shoe. Insurance is thus afforded that the heel will fit the shoe in the most satisfactory manner. The upper may be held under pressure a few seconds if desired, after which the operator returns the mold 98 and the member 100 to their initial positions, releases the shoe support 14 and removes the shoe.

Having described the invention, what I claim as new and desire to secure by Letters Patent of the United States is:

1. In a machine for shaping the heel ends of uppers, a mold constructed and arranged to extend about the heel end of an upper on a form and by contact with the upper adjacent to the edge of the heel seat to establish a definite edge line on the upper about the heel seat upon the application of pressure heightwise of the form to an inturned marginal portion of the upper, said mold being flexible to permit it to assume different contours, and means for determining independently of the form the contour lengthwise of the edge of the heel seat of that portion of the mold which engages the upper adjacent to the edge of the heel seat.

2. In a machine for shaping the heel ends of uppers, a mold constructed and arranged to extend about the heel end of an upper on a form and by contact with the upper adjacent to the edge of the heel seat to establish a definite edge line on the upper about the heel seat upon the application of pressure heightwise of the form to an inturned marginal portion of the upper, said mold being flexible to permit it to assume different contours, and a templet having a contour geometrically similar to the desired contour of the edge line of the heel seat and arranged

to determine in that respect the contour of that portion of the mold which engages the upper adjacent to the edge of the heel seat.

3. In a machine for shaping the heel ends of uppers, means for laying the marginal portion of the heel end of an upper inwardly over a form and for thereafter applying pressure heightwise of the form to that portion of the upper, and a flexibly adjustable mold constructed and arranged to serve as a backing for the upper about its heel end adjacent to the edge of the heel seat to establish a definite edge line on the upper about the heel seat when the pressure is thus applied to the overlaid margin of the upper, a portion of the machine having a contour geometrically similar to the desired contour of the edge line of the heel seat and arranged to determine in that respect independently of the form the contour of that portion of the mold which engages the upper adjacent to the edge of the heel seat.

4. In a machine for shaping the heel ends of uppers, means for laying the marginal portion of the heel end of an upper on a form inwardly over the bottom of the form, a pressing member for thereafter applying pressure heightwise of the form to the overlaid marginal portion of the upper, and a flexibly adjustable mold constructed and arranged to serve as a backing for the upper about its heel end adjacent to the edge of the heel seat to establish a definite edge line on the upper about the heel seat when the pressure is thus applied to the overlaid marginal portion of the upper, said pressing member having a contour geometrically similar to the desired contour of the edge line of the heel seat and arranged to determine in that respect independently of the form the contour of that portion of the mold which engages the upper adjacent to the edge of the heel seat.

5. In a machine for shaping the heel ends of uppers, a substantially U-shaped mold flexibly adjustable to different contours and arranged to extend about the heel end of an upper on a form, said mold including a rubber pad yieldable upon contact with the upper and having also a portion of harder material for engaging the upper adjacent to the edge of the heel seat to establish a definite edge line on the upper about the heel seat upon the application of pressure heightwise of the form to an inturned marginal portion of the upper, and a templet for controlling said mold to determine independently of the form the contour lengthwise of the edge of the heel seat of that portion of the mold which engages the upper adjacent to the edge of the heel seat.

6. In a machine for shaping the heel ends of uppers, a substantially U-shaped mold flexibly adjustable to different contours and arranged to extend about the heel end of an upper on a form, said mold including a flexible metal band and having also a molding member arranged to engage the upper adjacent to the edge of the heel seat to establish a definite edge line on the upper about the heel seat upon the application of pressure heightwise of the form to an inturned marginal portion of the upper, and a templet arranged to engage a marginal portion of said band to determine independently of the form the contour lengthwise of the edge of the heel seat of that portion of the mold which engages the upper adjacent to the edge of the heel seat.

7. In a heel-end lasting machine, a mold constructed and arranged to extend about the heel end of an upper on a last and by contact with

the upper adjacent to the edge of the heel seat to establish a definite edge line on the upper about the heel seat upon the application of pressure heightwise of the last to the marginal portion of the upper over an insole on the last, said mold being flexible to permit it to assume different contours, and a templet arranged to determine independently of the last the contour lengthwise of the edge of the heel seat of that portion of the mold which engages the upper adjacent to the edge of the heel seat.

8. In a heel-end lasting machine, a mold constructed and arranged to extend about the heel end of an upper on a last and by contact with the upper adjacent to the edge of the heel seat to establish a definite edge line on the upper about the heel seat upon the application of pressure heightwise of the last to the marginal portion of the upper over an insole on the last, said mold being flexible to permit it to assume different contours, means for applying the mold about the heel end of the upper, and a templet having a contour geometrically similar to the desired contour of the edge line of the heel seat, said templet being arranged to be engaged by a portion of the mold as it is applied about the heel end of the upper to determine the position of the mold lengthwise of the last and also the contour lengthwise of the edge of the heel seat of that portion of the mold which engages the upper adjacent to the edge of the heel seat.

9. In a heel-end lasting machine, means for laying the marginal portion of the heel end of an upper on a last inwardly over an insole on the last, a pressing member for thereafter applying pressure heightwise of the last to the overlaid marginal portion of the upper, and a flexibly adjustable mold constructed and arranged to serve as a backing for the upper about its heel end adjacent to the edge of the heel seat to establish a definite edge line on the upper about the heel seat when the pressure is thus applied to the overlaid marginal portion of the upper, said pressing member being so formed and arranged as to serve as a templet for determining the contour lengthwise of the edge of the heel seat of that portion of the mold which engages the upper adjacent to the edge of the heel seat.

10. In a heel-end lasting machine, wipers movable to wipe the margin of the heel end of an upper on a last inwardly over an insole on the last, means for thus moving said wipers and for then retracting them from over the upper, means for thereafter applying pressure heightwise of the last to the overwiped margin of the upper, a flexibly adjustable mold constructed and arranged to serve as a backing for the upper about its heel end adjacent to the edge of the heel seat to establish a definite edge line on the upper about the heel seat when the pressure is thus applied, means for applying said mold about the heel end of the upper after the wipers have been retracted, and means for determining independently of the last the contour lengthwise of the edge of the heel seat of that portion of the mold which engages the upper adjacent to the edge of the heel seat when the mold is applied about the heel end of the upper.

11. In a heel-end lasting machine, wipers movable to wipe the margin of the heel end of an upper on a last inwardly over an insole on the last, means for thus moving said wipers and for then retracting them from over the upper, a pressing member for thereafter applying pressure heightwise of the last to the overwiped mar-

gin of the upper, a flexibly adjustable mold constructed and arranged to serve as a backing for the upper about its heel end adjacent to the edge of the heel seat to establish a definite edge line

5 on the upper about the heel seat when the pressure is thus applied, and means for applying said mold about the heel end of the upper after the wipers have been retracted, said pressing member being so formed and arranged as to serve 10 as a templet in engagement with a portion of the mold as the mold is applied to the upper for determining the contour lengthwise of the edge of the heel seat of that portion of the mold which engages the upper adjacent to the edge 15 of the heel seat.

12. In a heel-end lasting machine, the combination with means for supporting a last and shoe for a heel-end lasting operation, of a substantially U-shaped mold constructed and arranged 20 to extend about the heel end of the shoe and by contact with the upper adjacent to the edge of the heel seat to establish a definite edge line on the upper about the heel seat upon the application of pressure heightwise of the last to the marginal portion of the upper over an insole on the last, said mold being flexibly adjustable to different contours and being also angularly movable laterally upon engagement with the upper to permit it to assume different positions in 25 accordance with differences in the positions of different shoes, and a templet for engaging said mold to determine independently of the last the contour lengthwise of the edge of the heel seat of that portion of the mold which engages the upper adjacent to the edge of the heel seat, said templet being angularly movable about an axis extending heightwise of the last upon engagement of the mold therewith to permit it to assume in that respect positions corresponding to 30 different positions of the mold.

13. In an upper-shaping machine, a plurality of wipers movable inwardly about an end of an upper on a form to wipe the margin of the upper over the form, said wipers being thus movable 45 inwardly in converging paths meeting in a plurality of locations over the margin of the upper to localize between them by their approach to one another any pleats formed in said margin and being provided with means for trimming said pleats by their inward wiping movements.

14. In an upper-shaping machine, a plurality of wipers comprising an end wiper, side wipers and corner wipers rectilinearly movable inwardly in converging paths about an end of an upper on a form to wipe the margin of the upper over the form and to localize between them by their approach to one another any pleats formed in said margin, said wipers having means for trimming said pleats by their inward wiping movements.

15. In an upper-shaping machine, a plurality of wipers movable inwardly in converging paths about an end of an upper on a form to wipe the margin of the upper over the form and to localize between them any pleats formed in said margin, said wipers having edges arranged to cooperate with one another to trim said pleats by a shearing action thereon in response to the approach of the wipers to one another in their inward wiping movements.

16. In an upper-shaping machine, a plurality of wipers movable inwardly about an end of an upper on a form to wipe the margin of the upper over the form, said wipers being thus rectilinearly movable inwardly in converging paths meeting in a plurality of locations over the margin of the

upper to localize between them any pleats formed in said margin and having opposed parallel edges arranged to cooperate with one another to trim said pleats by a shearing action thereon in response to the approach of the wipers to one another in their inward wiping movements.

17. In an upper-shaping machine, a plurality of wipers comprising an end wiper, side wipers and corner wipers movable inwardly in converging paths about an end of an upper on a form

10

to wipe the margin of the upper over the form and to localize between them any pleats formed in said margin, said corner wipers having edges arranged to cooperate respectively with edges on said end wiper and side wipers to trim said pleats by a shearing action thereon in response to the approach of the wipers to one another in their inward wiping movements.
